KIER

Application filed March 23, 1931. Serial No. 524,438.

The principal objects of this invention are to provide for automatically regulating the circulation in a kier to overcome the possibility of a bad boil and to provide simple and effective means and method for allowing the liquor at the center of the kier to flow out and in by gravity without obstruction by the goods therein.

Other objects and advantages of the invention will appear hereinafter.

Reference is to be had to the accompanying drawing in which the figure is a diametrical sectional view of a kier constructed in accordance with this invention.

The sizing materials now usually contain mineral oils and corn starch or other unsaponifiable materials which are apt to obstruct the flow of liquor so as to pull the well dry under the grates and choke the top especially of a pump operated kier. This trouble is apt to last until the mass of liquor and goods gets to a certain temperature high enough to melt these materials. Unless the temperature is raised slowly and evenly at the start, gummy substances are formed in masses throughout the kier and a bad boil follows. It is very important that the circulation shall be brought up to the maximum of the pump as soon as possible and kept at that maximum throughout the boil.

One of the objects of this invention is to secure automatic regulation of the circulation, as will appear, so that the temperature will be raised slowly and evenly at the start and afterwards kept constant, thus avoiding the above mentioned difficulties.

The automatic control is dependent upon the liquor below the grate. If for any reason that in the goods above the grate does not come down fast enough the liquor below the grate will be pumped out and loaded on top of the goods and my automatic regulation is controlled by the level in the well.

Another feature of the invention relates to the fact that the kier is packed to the

proper load of goods and it is well known that there is seldom any difficulty with the treatment of the goods around the circumference of the kier for a certain space from the outer walls. It is in the center that the trouble usually occurs. There is no way for the liquor to drain through the goods except of course by gravitation to the pump, for well known reasons, a pump cannot act to help it. For the purpose of allowing the liquor to come down through at the center I employ an equalizing pipe in the heart of the mass, perforated so that the liquor can work down and out through the goods. Of course, this keeps the goods uniformly saturated with the liquor as it drains out and back until near the bottom. In other words, the liquor at the center can enter this pipe through the perforations and work to the bottom of the goods by gravitation in the above method. The percolation of the liquor down through the goods is equalized by the center pipe and in this way the goods are treated as well at the center as they are at the circumference of the kier.

In the form shown I have illustrated a well known type of kier 10 having a steam heating coil 11 in the well below the grate 12 for heating the liquor therein by indirect heat or radiation. From the bottom of the kier is a discharge pipe 13 which is connected with a drain 14 by a draw-off valve 15. It is also connected through a pipe 16, preferably having a valve 17, with a pump 18. The discharge pipe 19 of this pump is connected with a vertical pipe 20 which extends up to the top of the kier outside and is connected with a spraying device or nozzle 21 for spraying the liquor into the top of the kier and spreading it all over it. There is a connection between the pipe 16 and the nozzle 21 normally closed by a bypass valve 22.

As stated above, under certain circumstances, the liquor in the well below the grate

- 12 can drop down and a liquid level can be formed. Now for the purpose of operating the valve 22 automatically I provide two pipes 23 and 24, one extending from 5 the kier just above the grate, preferably, and the other from near the bottom of the well. They are both connected with a simple form of closed tank or receptacle 25. Now obviously if the level of the liquor in the 10 well drops a corresponding level will appear in this tank 25 and will always keep even with that of the liquor in the well. Under ordinary circumstances the well is always full of liquor and also this tank. 15 In this tank I place a float 26 of any desired kind on an arm 27 pivoted in the walls of the tank at 28 and having an arm 29 outside, which is connected to the valve 22 to open and close it.
- 20 Under normal operation of the kier the float is always as high as possible and the valve 22 is closed. Ordinary leakage through it will not materially affect its operation but it is closed under normal operation 25 of the kier. It opens only when the unusual circumstance happens that the pump is drawing out the liquor faster than it is draining down from the cloth, and the level gets down low enough so that possibly the 30 heating coil may be exposed to the air and there might be a possibility of the water being drawn out and the well being left dry. Thus the valve 22 is opened slightly and less liquor is pumped into the kier at the top, 35 while some may even be pumped in at the bottom or, at least, it will be withdrawn from the bottom more slowly.
- The other of the two important objects 40 of the invention is accomplished in a very simple manner. At the center of the kier is the usual central relief pipe 30 which is open at the bottom and also at the top and extends up above the line of liquor in the kier. This allows liquor to be projected up 45 through it if any unusual pressure is exerted in the well below the grate.
- I take advantage of the use of the pipe 50 30, which terminates at the grate, to employ an equalizing means for assisting gravity in draining liquor out of the cloth at the center of a kier. This is in the form of a 55 perforated pipe 31 extending from the bottom of the pipe 30, that is, from the grate, practically up to the liquor line. This pipe surrounds the pipe 30 and is considerably 60 larger so as to provide a space between the two and is provided with perforations. The perforations are comparatively frequent at the top and grow more sparse at the bottom.
- 65 As explained above it is difficult to secure even treatment of the goods under the present conditions of treating cotton and that is due to the fact that the liquor cannot descend as rapidly at the center where the goods are packed tightly. Now with this

equalizing pipe 31 the liquor that gathers around the center can enter this pipe and flow out and in to the lower portion of the mass.

I may say that I have found a pipe having eighty-four $\frac{3}{4}$ " holes very suitable for this purpose if the holes are distributed in the manner shown. That is, in the top part of the pipe throughout the first three feet there are eight holes in a row around the pipe and nine rows equally spaced apart. Below this section of the pipe the holes are arranged four in a row. In the first space of six inches there is a single row of four holes and in the next foot there are four more holes in one row and in the next six inches one row of four holes making twelve in all. This is given as an example to show how these holes may be arranged but the idea is that there are many at the top and few at the bottom. This equalizing pipe is not connected to the pump or to the drain but is closed at the bottom. It improves the circulation in the heart of the mass by allowing the liquor to work out and in freely at the center and work more freely toward the bottom, thus getting a more uniform drop throughout the mass in the kier. This object is performed without the use of force but by the natural action of gravitation.

Under ordinary operation, with the balanced by-pass valve 22 closed and everything working well, the float 26 will stay at the top of the tank 25 and keep the valve 22 closed. The valve 15 also is closed. The pump 18 operates and forces the liquor into the kier at the top. I not only get the ordinary percolation of the liquor downwardly through the goods, but at the center I get an additional drop of the liquor through the 105 pipe 31. This may be considered as excess liquor and it comes out and in the pipe toward the bottom and drains toward the well.

Although I have illustrated and described a single embodiment of this invention and indicated the steps through which the liquor goes in the normal operation, I am aware of the fact that modifications can be made both in the apparatus and in the process, by any person skilled in the art, without departing from the scope of the invention as expressed in the claims. Therefore I do not wish to be limited in this respect but what I do claim is:—

1. In a kier, the combination with a grate, 120 of an equalizing pipe extending from the grate upwardly practically to the liquor line, said equalizing pipe being provided with perforations for admitting liquor from the kier and being closed at the bottom.

2. In a kier, the combination with a grate and a center relief pipe, of an equalizing pipe extending from the grate upwardly around the center relief pipe, practically to 130 the liquor line, said equalizing pipe being

spaced from the relief pipe to provide a space therein through which liquor can freely work out and in, the equalizing pipe being provided with perforations.

- 5 3. In a kier, the combination with a relief pipe, of an equalizing pipe extending around the center relief pipe, said equalizing pipe being spaced from the relief pipe to provide a space therein through which liquor can
10 freely work out and in, the equalizing pipe being provided with many perforations in the upper part thereof and with a smaller number in the lower part.

In testimony whereof I have hereunto affixed my signature.

EUGENE D. JEFFERSON.
